ANTIGLARE DEVICE FOR HEAD LAMPS

Wendel Badem, Milwaukee, Wis.

Application August 15, 1939, Serial No. 290,299

1 Claim. (Cl. 240—48.4)

This invention relates to an antiglare device for head lamps, the general object of the invention being to provide a perforated metal plate which bears against the inner face of the lens of the head lamp and the plate constructed and arranged that it will prevent the rays of light from the lamp from blinding drivers of other cars.

This invention also consists in certain other features of construction and in the combination and arrangement of the several parts to be hereinafter fully described, illustrated in the accompanying drawing and specifically pointed out in the appended claim.

In describing the invention in detail, reference will be had to the accompanying drawing wherein like characters denote like or corresponding parts throughout the several views, and in which:

Figure 1 is a view looking toward the device when placed in a head lamp.

Figure 2 is a fragmentary portion of the device enlarged to show how the perforations are punched therein.

Figure 3 is an elevation of the head lamp with parts in section showing how the same is arranged therein.

As shown in this drawing the device A is formed of a metal plate 1 of a shape to fit in the front end of the head lamp L directly in rear of the transparent member 2 of the lamp, the metal plate being provided with the bent ears 3 which fit over the front end of the lamp casing and is held in place by the rim 4 which holds the transparent member 2 in place. Of course, the member can be held in place in any other suitable manner. The metal plate is punched by a square punch to form the projections 5 and, of course, these projections extend from one face and form recesses in the other face and in punching the metal a four-point star-shaped opening 6 is formed in the metal. The projections extend outwardly and engage the inner face of the transparent member as clearly shown in Figure 3. The member 1 has its lower part cut on a straight edge as shown at 8 and this is spaced above the lower part of the lamp so that rays can pass under the member 1 without being effected thereby. However, the other rays must pass through

the holes 6 and they prevent the rays of light coming from the lamp from blinding drivers of other cars or vehicles approaching the vehicle with the improved device thereon.

The plate is chromium plated on the inside face so that the rays of light striking said plate face are reflected back to the reflector of the head lamp which then throws them out through the holes onto the road. The plate can be bent to fit the contour of the lens of the lamp with which the device is used. The punching not only forms the holes therein of special shape but these projections strengthen the device or plate. This device will prevent the rays of light from the head lamps from blinding other drivers and yet will not interfere with the proper illumination of the road by the lamps.

It is thought from the foregoing description that the advantages and novel features of the invention will be readily apparent.

It is to be understood that changes may be made in the construction and in the combination and arrangement of the several parts provided that such changes fall within the scope of the appended claim.

Having described the invention, what is claimed as new is:

A nonglare attachment for a head lamp comprising a metal plate having four-sided projections of hollow construction extending from one face thereof with the spaces formed by the projections opening out through the other face, the sides of each projection sloping inwardly and forwardly and each side being of triangular shape and said sides of each projection being slightly spaced apart with the spaces gradually increasing in width to the small end of the projection and means for holding the plate in a head lamp with the said front ends of the projections engaging the inner face of the transparent member of the lamp, the inner face of the plate and the inner walls of the projections being reflective, the bottom of the plate being straight and spaced from the lower part of the lamp to form a space at the lower part of the transparent member un-covered by the plate.
